CIRCUIT BREAKER

James M. Cunningham, Endicott, N. Y., assignor
to International Business Machines Corporation,
New York, N. Y., a corporation of New
York

Application May 27, 1943, Serial No. 488,714

2 Claims. (Cl. 200—33)

This invention relates to circuit breakers and more particularly to cam operated contacts for making and breaking an electrical circuit.

The general object of the instant invention resides in the provision of improved cam means for operating electrical contacts according to selectively adjustable timing requirements.

More specifically, it is an object to provide a rotatable member with a pair of novel cam elements universally adjustable to enable one element to close the contacts at any point in a cycle of rotation and the other element to reopen the contacts at any other point in the cycle.

A still further object is to provide novel contact blade shifting mechanism intermediate an operating cam and the contact blade, which mechanism comprises a resiliently telescoping sleeve and plunger which effect a positive control over the opening and closing of the contacts, thereby minimizing arcing conditions.

Other objects of the invention will be pointed out in the following description and claims and illustrated in the accompanying drawing, which disclose, by way of example, the principle of the invention and the best mode, which has been contemplated, of applying that principle.

In the drawing:

Fig. 1 is an assembly view of the circuit breaker in side elevation with parts broken away to show interior construction.

Fig. 2 is a sectional view taken substantially along lines 2—2 of Fig. 1.

Fig. 3 is a view similar to Fig. 1 with parts in operated position.

Referring to the drawing, 10 represents a supporting frame in which is journaled a shaft 11. The shaft is arranged to be driven in a clockwise direction as viewed in Fig. 1 by any suitable power means (not shown). Fastened to the shaft in a predetermined relationship by means of a set screw 12 is a circuit closing cam 13, and on the hub thereof is carried an unlatching member 14 which is held in position on the hub by a headed screw 15 which extends through a slot 16 in the member. The hub of cam 13 is provided with four tapped holes spaced 90° apart, so that member 14 may be initially adjusted through the insertion of screw 15 in any of the four holes. The set screw 12 will, of course, be inserted in one of the three other positions. The slot 16 in member 14 extends for 90° so that with screw 15 in any hole the member 14 may be rotated, after screw 15 has been loosened, to any rotative position within the 90° range of slot 16, and the screw 15 is then tightened.

By the described construction, it is apparent therefore that cam 13 and member 14 may be given any relative relationship so that a given point on each will be any angular distance apart.

5 Located above shaft 11 is a plunger 17 having a head 18 lying in the path of cam 13, which head is engaged by the cam and elevated thereby. The plunger 17 is slideable in a sleeve 19 which is freely slideable in a suitable bore in a bracket 20 of 10 insulating material. A spring 21 acts to urge plunger 17 downward within sleeve 19 and a shoulder 22 acts as a limit stop for such downward movement, while a plate 23 acts as a limit stop for the downward position of both sleeve and plunger.

The upper end of sleeve 19 is provided with a plug 24 above which is positioned the contact 25 carried by resilient blade 26 for cooperation with fixed contact 27.

20 In the operation of the device, as the cam 13 rotates, it engages head 18 and rapidly elevates plunger 17 against the action of spring 21, compressing the spring and causing it to act against shoulder 22 to elevate sleeve 19 and plug 24 25 against blade 26. This results in closure of the contacts 25, 27. The transmission of power from cam 13 is accordingly through spring 21 which overcomes the resiliency of blade 26 and exerts a positive closing action on contacts 25, 27 and prevents contact 25 from bouncing away from contact 27, thereby minimizing arcing condition.

Pivoted at 29 on bracket 20 is a lever 32 which is normally urged clockwise about its pivot by a compression spring 30, so that when head 18 is 35 elevated by cam 13 latching edge 31 of lever 32 snaps under an edge 33 of head 18 to hold the contacts closed. It is to be noted that cam 13 will raise head 18 high enough to provide clearance for latching edge 33 to swing into latching 40 position, after which the head will move down slightly to seat itself on the latch. This, however, will not disturb the engagement between contacts 25 and 27 as spring 21 will permit the necessary flexibility to enable head 18 to make 45 the slight descent without accompanying downward movement of sleeve 19.

Bracket 20 is secured to frame 10 by a bolt 35 extending through an elongated hole 36 in the frame, so that the entire bracket 20 may be 50 adjusted slightly in a vertical direction to obtain the necessary clearance in the stroke of head 18. After the contacts have been closed by cam 13 and latched by lever 32, member 14 will strike a depending arm 37 to rock lever 32 counterclockwise to release head 18 whereupon spring 21 will

urge plunger 17 down and resilient blade 26 will urge sleeve 19 in the same direction through plug 24. The spring action will thus restore the parts to their initial positions.

There is thus provided what might be termed a universally timed circuit breaker in which alteration of the timing between the point of making and the point of breaking in a cycle is accomplished by circumferential adjustment of member 14 on cam 13, and the time of either make or break is adjusted by positioning of cam 13 on shaft 11.

Further, there is provided a positive closing action in which spring 21 exerts the initial closing force to bring contacts 25 and 27 together and thereafter continues to exert substantially the same pressure to maintain the contacts in circuit closing engagement.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. An electrical circuit controller comprising a support, a stationary contact mounted on the support, a movable spring member having a contact engageable with the stationary contact to make an electrical circuit, said spring member normally biasing its contact away from the stationary contact, a sleeve mounted for reciprocation in said support for engaging and moving said

spring member to contact closing position, a plunger slidably mounted within said sleeve, a spring within the sleeve for transmitting movement of the plunger to the sleeve, a cam for moving the plunger, said movement of the plunger causing corresponding movement of the sleeve through said spring to effect closure of the contacts, and a latch for engaging and holding said plunger in its moved position whereby the spring exerts a continuing force to maintain the contacts closed.

2. An electrical circuit controller comprising a support, a stationary contact mounted on the support, a movable spring member having a contact engageable with the stationary contact to make an electrical circuit, said spring member normally biasing its contact away from the stationary contact, a sleeve mounted for reciprocation in said support for engaging and moving said spring member to contact closing position, a plunger slidably mounted within said sleeve, a spring within the sleeve for transmitting movement of the plunger to the sleeve, a rotating cam for effecting a momentary movement of the plunger at a point in the rotation of the cam, said movement of the plunger causing corresponding movement of the sleeve through said spring to effect closure of the contacts, a latch for engaging and holding said plunger in its moved position whereby the spring exerts a continuing force to maintain the contacts closed, and a member adjustably secured to said cam for engaging said latch at another point in the rotation of the cam to release the plunger whereby said spring and contact spring member will effect reopening of the contacts.

JAMES M. CUNNINGHAM.
